UNITED STATES PATENT OFFICE.

EDWIN C. SHERWIN, OF BRANDON, WISCONSIN.

HOLDBACK.

SPECIFICATION forming part of Letters Patent No. 394,780, dated December 18, 1888.

Application filed July 16, 1888. Serial No. 280,053. (No model.)

To all whom it may concern:

Be it known that I, EDWIN C. SHERWIN, a citizen of the United States, residing at Brandon, in the county of Fond du Lac and State 5 of Wisconsin, have invented certain new and useful Improvements in Holdbacks; and I do declare the following to be a full, clear, and exact description of the invention, such as will enable others skilled in the art to which it app- 10 pertains to make and use the same, reference being had to the accompanying drawings, and to the letters and figures of reference marked thereon, which form a part of this specification.

15 This invention relates to holdback-fastenings for vehicle-thills, and has for its object to provide a fastening for securing the breeching-straps to the thills that will be simple, cheap, and efficient, and which will preclude 20 any accident arising from leaving the said breeching-straps fastened to the thills when unhitching the horse and letting the thills drop, and which will permit the breeching to become readily disengaged from the thills 25 when it is drawn forward, whether by design or by accident.

The improvement consists of a fastening composed of two plates that are hinged together at their front ends, the base-plate having 30 a tongue and the fastening-plate having an opening to receive the tongue and an eye or loop to receive the strap, as hereinafter will be more fully described and claimed, and shown in the annexed drawings, in which—

35 Figure 1 is a plan view of a pair of thills having my improvement applied; Fig. 2, a perspective view of the fastening, showing it open; Fig. 3, a top edge view of the fastening, showing its operation by dotted lines; and 40 Fig. 4, a modification.

The base-plate A—that is, the plate which is designed to be fastened to the thills—is provided with the openings *a*, through which screws or other fastening means pass to se- 45 cure it to the thills, and with the tongue *C*. The fastening-plate B, hinged at one end to the base-plate, is provided with the opening *b* to receive the tongue, and with the loop *D* at its free end to permit the passage of the 50 strap. The tongue *C* is sufficiently long to prevent its accidental displacement from the

strap, and is curved to facilitate its passage through the opening in the fastening-plate. The hinge-joint between the plates is wide enough to permit them to lie parallel and ac- 55 commodate the thickness of the strap between them.

In practice the fastening is applied so that its hinge end is forward, and is secured in any suitable manner to the thills, the breeching-strap *E* being passed through the loop *D* from the outside between the plates *A* and *B* and slipped over the tongue *C*. The strain being rearward and inward against the closed end of the loop *D*, holds the fastening-plate 65 closed. If from any cause the strain on the strap is forward, the plate *B* will open and the strap will become disengaged from the tongue and slip out through the loop and be freed from the thills. 70

In Fig. 4 the base-plate is shown provided with a lug, *e*, which crowds the strap in the loop *D* of the fastening-plate and relieves the tongue of some of the strain, the other parts of the fastening being substantially the same 75 as hereinbefore described and claimed.

Having thus described my invention, what I claim, and desire to secure by Letters Patent, is—

1. The herein-described holdback com- 80 posed of two plates hinged together at one end, the hinge-joint being sufficiently wide to permit the plates to lie parallel and have a space between them, one plate having the curved tongue, the other plate having an 85 opening for the passage of the tongue, and a loop at its end for the reception of the strap, substantially as described.

2. The holdback hereinbefore described, composed of two plates hinged together at 90 one end, one plate having a tongue and a lug, the other plate having an opening for the pas- sage of the tongue, and a second opening for the reception of the lug and the passage of the strap, substantially as set forth. 95

In testimony whereof I affix my signature in presence of two witnesses.

E. C. SHERWIN.

Witnesses:

MARTIN C. SHORT,
LEANDER FERGUSON.
